UNITED STATES PATENT OFFICE.

JEROME B. SECOR, OF CHICAGO, ILLINOIS.

DESIGN FOR SEWING-MACHINE FRAME.

Specification forming part of Design No. 5,407, dated December 5, 1871.

To all whom it may concern:

Be it known that I, JEROME B. SECOR, of Chicago, in the county of Cook and State of Illinois, have invented and produced a new and useful Design for Goose-Neck and Cloth-Plate for Sewing-Machine, of which the following is a specification, reference being had to the accompanying drawing which forms a part thereof.

Figure 1 is a side elevation representing my design, and Fig. 2 is a top or plan view representing the same.

A is the goose-neck. a is the spool-seat. b is the boss to hold the screw which attaches the vibrating arm to the goose-neck. c is the hole for the screw by which the cheek-lever is adjusted or regulated. d is the boss for the tension. f is the hole through which the needle-bar passes. g is the hole through which the cloth-presser bar passes. B is the chamber covering the cam-wheel which vibrates the vibrating-lever by mean of a bar passing through the slot b'. e' is

the bearing for the shaft. d' is that part of the bed-plate which rests upon the table. e' is a frame for strengthening the bed-plate. h is the cloth-plate. All the parts above described except the cloth-plate are to be formed as shown and may be cast in one piece. The cloth-plate may be cast in one piece and attached to the frame e', as shown.

All the parts included in this general description down to the letter h relate to what I term the goose-neck, and all the parts included therein, including and following the letter h, relate to what I term the cloth-plate.

I claim as my invention—

The design for a sewing-machine consisting of the goose-neck and cloth-plate, as shown and described.

J. B. SECOR.
